Primary Examiner — Kevin K Rudzinski*Assistant Examiner* — Kathleen L Jones(74) *Attorney, Agent, or Firm* — Davis Wright Tremaine LLP(57) **CLAIM**

The ornamental design for a passive multiplexer, as shown and described.

DESCRIPTION

FIG. 1 is a perspective view of a passive multiplexer showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings are for purposes of illustrating portions of the passive multiplexer that form no part of the claimed design.

1 Claim, 7 Drawing Sheets(56)
